Specification for Design.

Patented Jan. 24, 1922.

Application filed April 27, 1921. Serial No. 464,997. Term of patent 14 years.

To all whom it may concern:

Be it known that I, LOUIS A. FREEDMAN, a citizen of the United States, residing at New York city, in the county and State of New York, have invented a new, original, and ornamental Design for Bell Attachments for Electric Lights, of which the following is a specification, reference being had to the accompanying drawing, in which—

Figure 1 is a perspective view of a bell attachment for electric lights, showing my new design, and

Figure 2 is a plan view of the same.

I claim:

The ornamental design for a bell attachment for electric lights, as shown.

LOUIS A. FREEDMAN.
